UNITED STATES PATENT OFFICE

ARTHUR W. SUITER, OF WOONSOCKET, RHODE ISLAND, ASSIGNOR TO RUSSIA CEMENT COMPANY, OF GLOUCESTER, MASSACHUSETTS, A CORPORATION OF MASSACHUSETTS

BOTTLE-FILLING MACHINE

Application filed October 31, 1921. Serial No. 511,717.

This invention relates to bottle filling machines of that type which utilizes atmospheric pressure for forcing material into the bottle, this invention effecting this result by 5 producing a vacuum therein.

One feature of the invention relates to mechanism by which the filling is effected to a predetermined level, any excess material being returned automatically to the supply 10 reservoir.

The bottles are designed to be supported on a rotating turret, and the empty bottles being fed to a turret at one point, and the filled bottles removed at another point. A 15 further feature of this invention relates to means whereby the bottles may be filled as they are being moved between these points without danger of spilling the material or of interrupting the flow.

20 Yet another feature of this invention relates to means for handling the bottles and sealing and unsealing them with the vacuum producing mechanism.

An additional feature of this invention is 25 the means whereby a liquid seal is maintained between the rotating and non-rotating members of the suction element, thus avoiding the use of a stuffing box.

A further feature comprises the mechanism by which the required amount of vacuum is maintained.

30 Further objects and advantageous details and combinations of parts will appear from a more complete description of an embodiment thereof disclosed in the drawings in which

Figure 1 is a front elevation partly broken away of the machine.

Figure 2 is a half top elevation and half 40 section on line 2—2 of Figure 1.

Figure 3 is a plan partly in section of the supply tank and vacuum pipe system.

Figure 4 is a section on line 4—4 of Figure 1.

45 Figure 5 is a vertical cross section with parts removed or broken away through the central portion of the machine.

Figure 6 is a similar view of the vacuum tank at the top of the machine.

50 Figure 7 is a diagrammatic vertical sec-

tion illustrating the operation of the machine.

Figure 8 is an enlarged sectional detail of the bottle sealing mechanism.

Referring to these drawings at 1 is indicated a supporting standard for the machine parts. Positioned to rotate on a vertical axis on a hollow frusto-conical member 1^a fixed to the support 1 is a turret 2 which may be turned by any suitable means, herein shown a gear 3 being fixed thereto and through which turning movement may be imparted. 55

At the top of the turret 2 is a vacuum chamber 4 mounted to rotate therewith and beneath the turret fixed to the support 1 is a liquid supply tank 5. This supply tank may be supplied with liquid with which the bottles are to be filled through a pipe 6 (see Figures 5 and 7), a float 7 controlling the level of the liquid in the tank acting on a valve 8. Extending downwardly through the tank 5 is a vacuum pipe 9 fixed in a stationary position and extending upwardly axially of the turret 2 and communicating at its upper open end with the upper portion 65 of the vacuum chamber 4. This pipe may be threaded at its lower end in the base of the supply tank as shown in Figure 5, a pipe 10 communicating therewith and adapted to be connected to a vacuum pump. 70

As shown more particularly in Figures 5, 6, and 7 a tube 11 surrounds the pipe 9 and is spaced therefrom to afford an annular liquid sealing chamber 12. This tube 11 is made fast to the turret, as herein shown a connection being made at its upper end at 13 with the lower end of the vacuum chamber, the space 12 being in communication therewith. The lower end of the tube 11 projects downwardly beneath the surface of the liquid in the supply tank, and the pipe and tube are of sufficient vertical length so that when the vacuum chamber is partially exhausted atmospheric pressure on the surface of the liquid in the supply tank raises this liquid 75 to partially fill the annular chamber 12, thus furnishing a liquid seal between the rotating turret and the stationary pipe 9 under a hydrostatic head substantially balancing the extent of vacuum. 80

100

Near the lower portion of the turret is provided a plurality of vertically extending guide members 15 for slidably supporting a series of plungers 16, each plunger having at its upper end a shallow bottle-receiving receptacle 17. These receptacles may be made fast to the plungers by any suitable means, this means as shown consisting of a set screw 18 passed through a boss 19 depending from the base of each receptacle and engaging the upper reduced extremity 20 of the corresponding plunger 16.

Each receptacle 17 has an upstanding marginal flange 21 about a portion of its periphery, this flange being cut away at 22 to allow the bottles to be moved in and out by a sliding motion. The lower end of each plunger is provided with an outstanding flange or head 23. Each plunger is also guided preferably by a key within the member 15 to prevent relative rotation thereof so that the cut out portions 22 of the flanges 23 are held outwardly directed from the center of the turret.

The receptacles 17 are designed to receive the bottles to be filled, the bottles being fed in position in sequence at the point *a* as shown in Figure 4 to be filled, and removed at the point *b*. The bottles pass from the point *a* by rotation of the turret in a clockwise direction as viewed in Figure 4 to the point *b* and are filled while being moved as will later appear.

Positioned above each receptacle 17 and vertically slidable in the turret is a pair of rods 30 and 31. The lower end of the rod 31 has fixed thereto a sealing head comprising an annular plunger member 32 having its lower face formed so as to be brought into sealing engagement with the top of the mouth 10 of the bottle supported by the receptacle 17. The rod 30 carries at its lower end a filling head or plunger 33 adapted to be brought into sealing engagement with the head 32. Sealing engagement between the head 32 and the bottle top and the plunger 33 is effected by a member 36 carried by the head 32 and contacting at opposite ends with the bottle mouth and the plunger 33. The head 32 is provided with a central aperture 34 within which may telescope loosely a tube 35 fixed in the plunger 33. Projecting downwardly within the tube 35 and spaced therefrom is a second tube 37 which communicates at its upper end with a passage 38 in the plunger 33. The annular space between the tubes 36 and 37 communicates with a second passage 39 in the head 33. The passage 38 is connected by a flexible pipe 40 to the upper end of a pipe 41 which projects downwardly beneath the liquid in the supply tank 5, the pipes 40 and 41 being carried by the turret to rotate therewith. The passage 39 has communicating therewith a flexible pipe 42 which extends upwardly and is attached to a nipple 43 on the under side of the vacuum chamber.

Within the vacuum chamber is a substantially U-shaped pipe 44 communicating with each nipple 43 and having its discharge opening facing downwardly toward the pipe 9. For convenience, the pipes 40 and 41 will be referred to as the siphon pipe and pipes 42 and 44 as the suction pipe.

The heads 32 and 33 are normally held downward in separated position by means of springs 50 and 51 surrounding them and bearing at their upper ends against a flange 52 on the turret through which the rods are slidably, and at their lower ends against collars 53 and 54 fixed to these rods. The lower limit of motion of rod 30 is determined by means of a collar 55 fixed thereto above the flange 52, and the lower limit of the rod 31 is determined by a collar 56 provided with an extension 57 perforated to slidably receive the upper end of the rod 30. When the collar 56 is in contact with the flange 52 the heads 32 and 33 are separated. The head 33 may also have a guide extension 58 thereon through which the lower end of the rod 31 passes.

It will be evident that if a bottle carried by any of the supports 17 is raised it first contacts the head 32 and is sealed thereto and on further raising thereof this head moves upwardly into sealing engagement with the head 33, the spring 51 yielding. Further upward motion of the bottle then moves both plungers in unison against the tension of the springs 50 and 51. As soon as this sealing engagement takes place, however, it is evident that a vacuum is produced in the bottle by means of its communication through the annular passage between the tubes 35 and 37 through the passage 39 and the suction tube to the vacuum chamber, and that liquid is thus drawn up through the siphon pipe and discharged through the tube 37 into the bottle (as shown at the left in Figure 7), this action taking place until the level of the liquid reaches the lower end of the tube 34, whereupon the liquid is raised up between this tube and tube 37 into the passage 39 and up in the suction pipe toward the vacuum chamber.

In order to effect the sealing and unsealing of the bottles, automatic mechanism for raising the bottles into sealing engagement with the heads in the position *a* as shown in Figure 4 is provided. This means comprises a vertically movable bar or rod 60 slidably through a boss 61 fixed to the frame portion 1. The lower end of this bar is connected through a pivoted link 62 to an arm 63 fixed to a rock shaft 64. This rock shaft is actuated at suitable times by an arm 65 fixed thereto to which is pivotally connected a link 66 engaging one arm of a bell crank lever 67. This bell crank lever is fulcrumed at 68 and the arm 69 thereof has a cam follower 70 riding in a groove 71 in a cam wheel 72. This cam wheel may be driven in any suit-

able manner in time with the rotation of the gear 3. As herein shown this cam wheel is carried by a shaft 700 having a bevel pinion 701 thereon meshing with a bevel gear 702 fixed at one end of a horizontal shaft 703. The opposite end of the shaft 703 carries a bevel pinion 704 meshing with a bevel gear 705. Mounted to revolve with the gear 705 is a gear 706 meshing with the gear 3. By the rocking of the shaft 64 by means of this cam the bar 60 is projected beneath the head 23 of each plunger 16 as it comes in position thereover after a bottle has been placed in its support 17, the bottle thereby being raised into sealing engagement with the heads 32 and 33 as above described. As soon as a plunger 16 is raised by the bar 60 it is so held by a pivoted latch 75 having a supporting surface 76 engageable beneath the head 23 and a flange 79 upstanding therefrom engageable with the side of the plunger. A latch 75 is provided for each plunger and is normally urged outward toward its respective plunger member by means of a spring 80 reacting between it and a portion of the turret. This latch holds the plunger upwardly while passing between the positions *a* and *b* in a clockwise direction. In order to release this latch so that the bottle may be retracted from sealing engagement with the heads 32 and 33 a cam plate 85 is fixed adjacent the periphery of the turret, this plate 85 having thereon a fin 86 inclined inwardly toward the center of the turret and engaging on the outer faces of the latch 75 to force them inwardly against their springs 80 as they approach the position *b*, at which position they are entirely retracted from beneath the head 23. The cam plate 85 has an upwardly inclined upper face 87 terminating in a flat portion 88 which is of sufficient height to hold the plunger 16 raised as the latch is released in order to prevent premature dropping of the plunger. This flat portion 88 also holds the head 23 in position to pass between jaws of a retracting head 89 fixed to the upper end of a vertically sliding bar 90. The inclined face 87 serves to guide the head 23 into proper position in case a latch should have failed to retain the plunger 16 raised. This bar 90 projects through a guide 91 carried by the frame 1 and is connected by means of a pivoted link 92 to an arm 93 also fixed to the rock shaft 64. Whenever therefore the rock shaft is moved to raise the rod 60 to move a bottle into sealing engagement with the heads 32 and 33 the retracting head 89 engaging the flange or head 23 forcibly depresses a bottle support to permit a filled bottle to move out of sealing engagement with the plungers 32 and 33, the spring 51 being sufficiently heavy to retain the bottle in its support until the seal with the filling head is broken and until the sealing head reaches the limit of its downward

motion. Further downward motion of the support thereafter frees the bottle from the sealing head. The bar 90 is positioned at the point *b* so that when the bottles are retracted they may be removed from their supports 17.

As before stated when the bottles become filled the liquid passes up through the suction tube toward the vacuum chamber 4. In order to regulate the height to which the liquid may be so drawn provision is made for determining the amount to which the vacuum chamber is exhausted. As shown in Figures 1 and 6 the vacuum chamber is provided in its top with a valve 100 which is urged into closing engagement with its seat 101 by means of a spring 102 surrounding its stem and bearing between a washer 103 surmounted by a pair of check nuts 104 threaded on the upper end of the valve stem 105, and the seat member 101. The tension of this spring is so adjusted as to cause this valve to open when the vacuum in the vacuum chamber exceeds the required amount. By this means the level of the liquid in the sealing chamber 12 and the maximum height to which it is raised in the suction pipes while being filled is maintained substantially at the point *c* as shown in Figure 7.

In order to observe the action of the filling mechanism this vacuum chamber is preferably formed of a cylindrical transparent member 110 as of glass, sealed at its top and bottom against base and cap members 111 and 112 which are tied together at intervals by means of tie rods 113.

In the operation of the device, therefore, as an empty bottle is raised into sealing engagement with the plungers 31 and 32 a vacuum is produced in the bottle and liquid is drawn up through the siphon pipe as shown in the left hand portion of Figure 7 until the bottle is filled to the level of the lower end of the tube 35. The liquid continues to flow, however, but into the suction tube until the point *c* is reached, whereupon flow stops, the vacuum in the chamber being insufficient to raise the column of liquid to any greater height. This action takes place while the turret is being moved and is completed before the bottle reaches the position *b*. When it reaches the latter position it is drawn downwardly out of sealing engagement with the plungers 32 and 33. This causes the lower end of the tube 37 to be drawn relatively upwardly above the surface of the liquid in the bottle whereupon air finds its way to the open lower end of this tube and the column of liquid in the siphon pipe draws the liquid therein upwardly, and the entire contents of this tube empties into the supply tank 5. The air is also allowed access to the annular space between the tubes 37 and 35 so that the vacuum in the suction pipe causes the liquid therein to flow upwardly and to empty into the vacuum chamber. This action of the device is shown diagrammatical-

ly in the right hand portion of Figure 7, the liquid in the siphon tube being shown partly drawn downwardly and the liquid in the suction tube being shown partly raised. By this means the excess liquid is prevented from 5 spilling as the seal is broken while it insures that sufficient liquid is present under all conditions to completely fill the bottle to the required height. It is also evident that should 10 any imperfections in the bottle so as to prevent sealing engagement thereof with the heads be present, a vacuum will not be maintainable therein and the bottle will therefore not be filled. This machine thus acts automatically to discover imperfect bottles and 15 refrains from filling these.

Having thus described an embodiment of this invention it should be evident that many changes and modifications might be made therein without departing from its spirit or 20 scope as defined by the appended claims.

I claim:

1. In a machine of the class described a revoluble turret, bottle holders carried by said turret, a liquid supply, a pipe extending into liquid in said supply and leading to the mouth of a bottle carried by each of said holders, a vacuum chamber carried by said turret, a pipe extending from said chamber to the mouth of each bottle, a stationary pipe extending axially of said turret and communicating with said chamber and through which said chamber may be exhausted, the machine being adapted to contain a liquid forming a seal between said stationary pipe and turret. 35

2. A machine of the class described comprising a revoluble turret adapted to carry bottles to be filled, a liquid supply, a vacuum chamber, means whereby said supply and chamber may be placed in communication 40 with the bottles whereby they may be filled, and a stationary pipe extending through said supply axially of and spaced from said turret and opening into said chamber, by which pipe said chamber may be exhausted, the space between said turret and pipe being in communication at opposite ends with the liquid in said supply and said vacuum chamber and adapted 45 to contain liquid to form an air tight liquid seal between the turret and said pipe. 50

3. In a machine of the class described, a support, a pair of plungers mounted in said support, a filling head on one of said plungers having a central stem provided with a pair of 55 passages therein, a sealing head on the other plunger having a perforation for the slidible reception of said stem and movable into sealing engagement with said filling head, a liquid supply, a vacuum chamber, pipes leading 60 from said supply and chamber, respectively, to said passages, and means for relatively moving a bottle on said support and said plungers to bring the mouth of said bottle into 65 sealing engagement with said sealing head

and then said sealing head into sealing engagement with said filling head.

4. In a machine of the class described, a revoluble turret, a plurality of vertically movable bottle holders carried by said turret, a pair of superposed heads, the upper of said heads having a pair of passages therethrough a pair of plungers spring-supported above each holder, each of said plungers carrying one of said heads, a liquid supply, a vacuum chamber, a pipe extending from said liquid supply to one of said passages, a pipe extending from the other of said passages to said chamber, means for raising said holder to press the mouth of an empty bottle held thereby into sealing engagement with the lower head and to move said head into sealing engagement with said upper head, and means for lowering each holder to lower the filled bottle, the lower head lowering therewith sufficiently to break the seal with 70 said upper head. 75

5. A machine of the class described, a revoluble turret, a plurality of vertically

90

movable bottle holders carried by said turret, a vacuum chamber carried by said turret, a pipe extending axially of and spaced from said turret, a liquid supply, the space between said turret and pipe opening at its upper end in said vacuum chamber and at its lower end beneath the liquid in said supply and adapted to contain liquid to form a liquid seal between the pipe and turret, siphon and suction pipes leading respectively from said supply and from said vacuum chamber and adapted to be brought into sealing engagement with bottles carried by said holders, means to raise said holders to make sealing engagement at one point in the rotation of said turret, means to maintain said sealing engagement during a portion of the rotation of said turret to allow the bottles to be filled, and means acting at a succeeding point in the rotation of said turret to break said sealing engagement and to allow the liquid in said siphon pipe to drain back into said supply and the liquid in said suction pipe to be drawn into said chamber. 95

100

6. A machine of the class described comprising a revoluble bottle-carrying turret, a liquid supply, pipes leading from said supply to bottles on said turret, a vacuum pipe, and means for establishing operative connections from said pipe to the bottles on said turret, comprising relatively movable parts spaced apart for a sufficient height to contain liquid under a hydrostatic head balancing the vacuum in said pipe, said space communicating with a source of liquid supply. 105

110

7. A machine of the class described comprising a revoluble bottle-carrying turret, a liquid supply, pipes leading from said supply to bottles on said turret, a vacuum pipe, and means for establishing operative connections from said pipe to the bottles on said 115 120 125 130

5   turret, comprising relatively movable spaced parts, said space being in communication with liquid in said supply and forming with liquid derived therefrom a seal between said relatively movable parts.

8. A machine of the class described comprising a support for a bottle, an annular member movable relative to said bottle on said support into and out of engagement 10 with the mouth of the bottle and having a bottle-engaging portion shaped to seal against the top of the bottle mouth and when in sealing engagement with said bottle holding it against said support, a filling head, and 15 said machine including means for relatively moving said filling head and annular member into and out of sealing engagement with each other while said member is in sealing engagement with said bottle.

20   9. A machine of the class described comprising a vertically movable bottle support, an annular member and a filling head normally supported in spaced relation above the mouth of a bottle carried by said support, 25 means for raising said support to effect engagement of the bottle mouth with said annular member and then engagement of said annular member with said filling head, and means acting on the descent of said support for first disengaging said filling head and annular member and then disengaging said annular member and bottle.

30   10. In a machine of the class described, a 35 revoluble turret for supporting bottles, a liquid supply, means for conducting liquid from said supply to said bottles, and means for producing vacuum conditions in said bottles including an element movable with the turret and a stationary element spaced from 40 said movable element to define therewith a chamber communicating with said vacuum producing means and the liquid in said supply.

45   11. In a machine of the class described, a 50 revoluble turret for supporting bottles, a stationary liquid supply axially of said turret, pipes movable with said turret and leading from beneath the level of liquid in said supply to the bottles, and means for producing 55 vacuum conditions in said bottles including an element movable with said turret and a stationary element coaxial with and spaced from said movable element for the reception of a liquid in said space for sealing said elements against the ingress of air therebetween, 60 said space being of sufficient height to contain a liquid column having a hydrostatic head balancing the vacuum and communicating with a source of liquid supply.

65   12. In a machine of the class described, a 65 revoluble turret for supporting bottles, a stationary liquid supply axially of said turret, pipes movable with said turret and leading from beneath the level of liquid in said supply to the bottles, and means for producing

vacuum conditions in said bottles including an element movable with said turret and a stationary element coaxial with and spaced from said movable element, said space being in communication with the liquid in said supply to effect a liquid seal between said elements. 70

75   13. In a machine of the class described, a revoluble turret for supporting bottles, a liquid supply arranged axially of said turret, a stationary pipe positioned axially of said turret and extending through said liquid supply, a pipe closed at its upper end arranged coaxially with said stationary pipe and spaced therefrom and revoluble with said turret, said stationary pipe opening at its top into said space, and the lower end of said space being in communication with said supply beneath the liquid level therein, pipes leading from the upper end of said space to the bottles, and vacuum-producing means connected to the lower end of said stationary pipe. 80

85   14. In a machine of the class described, a 90 revoluble turret for supporting bottles, a liquid supply arranged axially of said turret, a stationary pipe positioned axially of said turret and extending through said liquid supply, a pipe closed at its upper end arranged coaxially with said stationary pipe and spaced therefrom and revoluble with said turret, said stationary pipe opening at its top into said space, and the lower end of 95 said space being in communication with said supply below the liquid level therein, pipes leading from the upper end of said space to the bottles, vacuum-producing means connected to the lower end of said stationary pipe, and pipes revoluble with said turret leading from the liquid in said supply to the 100 bottles. 105

110   15. In a machine of the class described, a revoluble turret for supporting bottles, vacuum producing means, and means for operatively connecting said vacuum producing means and bottles on said turret including a member movable with said turret, and a stationary member spaced from said movable member to define a chamber for receiving a sealing liquid, said chamber being of sufficient height to contain a column of liquid having a hydrostatic head balancing the vacuum produced by said means and communicating with a source of liquid supply. 115

120   16. In a machine of the class described, a revoluble turret for supporting bottles, a liquid supply, and vacuum producing means including a pair of spaced relatively movable members defining therebetween a chamber communicating at its upper portion with said vacuum producing means and bottles and at its lower portion with the liquid in said supply, said chamber being of sufficient height to contain liquid having a hydrostatic head balancing the difference of pressure be- 125 130

tween that of said vacuum means and that on the surface of liquid in said supply.

17. In a machine of the class described, a revoluble turret for supporting bottles, a liquid supply, means for conducting liquid from said supply to said bottles, and means for producing vacuum conditions in said bottles including an element movable with the turret and a stationary element, said elements being spaced to receive a liquid therebetween under a hydrostatic head balancing the vacuum in said bottles and sealing against the admission of air, said space communicating with a source of liquid supply.

18. In testimony whereof I have affixed my signature.

ARTHUR W. SUITER.
